MANIFOLDING BOOK

Albert R. Lawson, Hamilton, Ontario, Canada; assignor to Appleford Paper Products, Ltd., Hamilton, Ontario, Canada

Application May 29, 1936, Serial No. 82,577

8 Claims. (Cl. 282—24)

This invention relates to improvements in manifolding devices and particularly to manifolding books of the sales book type wherein a plurality of records are made of each transaction. 5 An object of the invention is the provision, in a simple and practical manifolding structure comprising a plurality of superimposed manifolding sets or units, each including a plurality of record leaves, of means supporting at least one leaf of each set in such a manner that it may be pivotally swung from the position of use in the set to a position of non-use outside of the set. Preferably each set includes a one time carbon leaf mounted upon a pivot for swingable movement about the pivot to a position of non-use wherein the used carbon leaves are segregated outside of the set. The used leaves may be segregated into separate and distinct groups such as used carbon leaves in one group and used record leaves in another group. Thus segregated they may be retained in the book or one group may be removed as a group from the book for further disposition.

Another object is the provision of a manifolding book comprising a plurality of manifolding units each of which includes a plurality of record leaves and one or more carbon leaves and wherein the leaves that are to be retained in the book following use are so pivotally supported upon a leaf supporting pivot stud as to be capable of swingable movement about the stud to a suitable position of non-use. Preferably the leaves are so supported upon the stud as to be capable of swingable movement directly over the stud or swingable pivotal movement about the axis of the stud.

The improved book is preferably characterized by having a back which carries the stud and which back is also provided with a front cover having a pocket into which certain of the leaves, following use, may be swung. The leaves are so supported that, instead of being swung into the pocket, they may be swung to a position overlying the pocket. The front cover pocket may be formed by a side flap which, with the front cover itself, constitutes a side entrance pocket into which used leaves may be swung. This side flap may be swingably connected with the back or it may have one end attached thereto. The back itself is provided with an end flap which serves as a stop sheet and is adapted to be folded in between successive unused manifolding sets.

In one desirable form the book cover or carrier for the manifolding units is characterized in that it is adapted to receive a packet consisting of a

plurality of superimposed manifolding units and to retain the same therein for pivotal swingable movement so the separate sets or leaves may be swung from a position of use to a position of non-use, and wherein the carrier is so constructed as to facilitate the segregation of the used leaves into groups.

The improved manifolding device may be embodied in a duplicate book, a triplicate book or a book designed to provide any desired number of records of a transaction. The leaves which are mounted upon the stud for swingable movement may be provided with stubs which are directly mounted on the pivot stud. The leaf is detachably associated with its stub for ready separation therefrom and certain of the record leaves may be detachably connected together. For example, the original record leaf may form a part of the same sheet as the duplicate record leaf being connected therewith along a weakened line and folded thereover. A one time carbon leaf is associated in each set or manifolding unit. This carbon leaf may be mounted upon the stud for independent pivotal swinging movement thereabout or it may have a stub which is adhesively secured to the stub of a record leaf so that the carbon leaf and record leaf swing as a unit. The carbon leaf may even be adhesively attached to the back of the original record leaf or secured in some other manner within the unit without being itself independently pivotally mounted upon the pivot stud.

In the triplicate type of book a heavy duty carbon leaf may be provided for successive use through the successive sets and in conjunction with the one time carbon leaf which is provided in each set. The one time carbon leaf provided for each set may have a clean surfaced back adapted to take a record from an overlying carbon leaf so that three records of a transaction may be made with each unit, adding only two clean surfaced record leaves by employing the one time carbon leaf which serves both as a record and a transfer leaf.

The invention may be embodied in a manifolding book of double or triplicate type or even in a manifolding book having four or five record leaves for each set. Several modifications of the invention showing its embodiment in duplicate and triplicate books and exhibiting differences in structure and assembly are shown in the drawings and hereinafter described.

Various other advantages, characteristics and meritorious features of this invention will more fully appear from the following description, ap-

pended claims and accompanying drawings, wherein:

Figure 1 is a perspective of a book of the duplicate type embodying my invention,

5 Fig. 2 is a perspective of the record leaves in a single set of the duplicate book shown in Fig. 1,

Fig. 3 is an elevation of the carbon leaf used in each set in the book shown in Fig. 1,

10 Fig. 4 is a sectional view through a duplicate book of a slightly modified form to that shown in Fig. 1,

Fig. 5 is a section through a duplicate book of a second slightly modified form,

15 Fig. 6 is a fragmentary cross-section through the pivot of the triplicate book shown in Fig. 7,

Fig. 7 is a perspective of my invention embodied in a triplicate form of book,

20 Fig. 8 is a perspective of the two clean surfaced record leaves used in the triplicate form of book illustrated in Fig. 7,

Fig. 9 illustrates a modified form of triplicate book wherein there are five leaves, three of which are clean surfaced,

25 Fig. 10 illustrates a second modified form of triplicate book wherein there are three leaves, only two of which leaves serve also as transfer leaves,

30 Fig. 11 illustrates a third modification of a triplicate book wherein there are four leaves, two being clean surfaced record leaves and one record leaf also serving as a transfer leaf,

Fig. 12 is a perspective of a book cover showing modifications as compared with the covers illustrated in Figs. 1 and 7.

35 Fig. 13 is a cross-section taken on 13—13 of Fig. 12,

Fig. 14 illustrates a second modified form of cover and one adapted to receive the packet shown in Fig. 15, and

40 Fig. 15 illustrates a removable packet adapted to be received in the cover shown in Fig. 14 and embodying my invention.

The invention comprises the provision in a 45 manifolding device, including a plurality of manifolding units, of means securing the units together within the carrier or cover of a book in such manner that at least one leaf in each set is swingable about the axis of a pivot stud to a position of non-use outside of the packet of manifolding units. Preferably a plurality of leaves in each set are so mounted upon the pivot that they may be so swung to a position of non-use and in so doing the leaves which are retained in the book following use may be segregated into 50 groups in their position of non-use. For example, each set may contain a carbon leaf which is pivotally supported to be swung after use to a position of non-use wherein the carbon leaves of successive sets are arranged in a group. Each unit 55 may also include a permanent record leaf which is likewise so pivotally supported that it may be similarly swung but disposed in its position of non-use in a group separate from the carbon leaf group. In this case provision is made in the book 60 or carrier for the separation of the two groups of used leaves. The invention is shown in a sample form in Figs. 1 to 5 in a book of the duplicate type wherein each unit is provided with two record leaves.

70 In the construction shown in Fig. 1 each unit comprises an original record leaf 20 and a duplicate record leaf 22. Each of these leaves is clean surfaced on both sides. The original record leaf is an integral part of the duplicate leaf being 75 folded thereover along a line of perforation 24.

It may be separated from a duplicate leaf along such perforated line. The duplicate leaf is provided with a stub 26. This stub is preferably an integral part of the leaf as shown in Fig. 2. The leaf is not adapted for severance from its stub 5 but it might be so formed according to conventional practice and as is shown in Fig. 8 where a line of perforation is provided separating the stub from the main portion of the leaf upon which the record is to be written. Each manifolding unit 10 includes in addition to the original and duplicate leaves 20 and 22 a carbon leaf 28 shown in Fig. 3. This is a one-time carbon leaf, being a thin sheet carbonized on one surface only. It contains a relatively thin coating of carbon as it is adapted 15 for the transfer of merely one record. Preferably each end of the leaf is provided with a margin which is free from carbon. This is shown at 30 at the lower end and at 32 at the upper end of the leaf. The marginal portion 32 is adhesively 20 adapted to be secured to the stub 26 of duplicate leaf 22 as shown in Fig. 1 and such adhesive coating is indicated on the stub 26 of the duplicate leaf 22.

The book shown in Fig. 1 is provided with a 25 plurality of sets or units made up as hereinabove described. Each unit includes two clean surfaced record leaves and a carbon leaf. The carbon leaf is adhesively secured at its stub to the stub of the duplicate record leaf. The original 30 leaf 20 is folded over the carbon leaf. Each of these units is mounted upon a pivot 34. The stub of the duplicate record leaf and the overlying stub of the carbon leaf adhesively secured thereto is provided with an aperture 27 adapted 35 to be received over the pivot. This pivot is carried by the back 36 of the book. The back has a front cover 38 which is adapted to fold over the superimposed manifolding sets. The back is also provided with a stop sheet 40 which is adapted 40 to be folded in between the unused sets and the set which is in position for use in the manner which is well understood. The front cover is provided with a side flap 42 which is adapted to fold inwardly over the front cover. It provides a pocket between the cover and the flap in which used leaves may be swung. This flap may be cut away as at 44 and 46 at two of its corners to expose the leaves thereunder in order that they may be readily grasped for manipulation. As shown in Fig. 1 this flap is free to 50 swing. The cut away portion 44 of the flap 42 is for the purpose of providing a clearance for the fingers of the operator on the act of swinging the leaf 28 into or out of the pocket over 55 the front cover. The cut away portion 46 is for the purpose of providing a clearance for the upper right hand corner of the leaf 28 when being swung into or out of the pocket.

In the manipulation of a book of this type 60 the stop sheet 40 will be inserted underneath the uppermost set before such set receives an entry. Upon the making of an entry upon the original leaf of such set this entry is transferred by the one-time carbon leaf to the duplicate leaf of the 65 set. The original record leaf may then be detached along the weakened line of severance 24 from the duplicate leaf and the duplicate leaf and carbon leaf may be swung as a unit into the pocket overlying the front cover 38 underneath its side flap 42. The stop sheet is then shifted to a position underneath the next succeeding set and the operation is repeated. It will be seen that the used leaves which are retained in the book form a stack of used leaves 70 75

within the pocket provided by the side flap on the front cover separate from the unused pack of leaves.

The construction of Fig. 4 is also a duplicate book but in this structure carbon leaf 28 is independently mounted upon the pivot 34 for swingable movement thereabout into the pocket independently of the duplicate record leaf. The duplicate record leaf 22 may be swung directly over the end of the pivot to a position overlying the flap 42 and this practice may be followed through the successive sets as they are used so that the used carbon leaves and the used duplicate record leaves will be segregated from each other into two groups of used leaves. This will facilitate disposition of one group or another as may be desired in the record system employed in the store and also to facilitate examination of the duplicate record leaves to check up on previous entries.

In Fig. 5 the carbon leaf 28 is adhesively attached at 45 at one end to the back of the original record leaf 20. When the original record leaf is separated along a perforated line 24 from the duplicate record leaf the carbon leaf comes off with the original record leaf. It may be readily separated therefrom so that the original record leaf can be handed to the customer as a clean surfaced leaf. The carbon leaf may be thrown away. The duplicate leaf 22 may be swung about the pivot into the pocket overlying the front cover. It will be seen therefore that Figs. 1, 3, and 5 illustrate three modifications of my invention in a duplicate type of book.

The triplicate book is shown in Figs. 7 to 11 and in Fig. 15. In the form of triplicate book shown in Fig. 7 there is provided a back 36, front cover 38, stop sheet 40, and front cover flap 42 as described in connection with the duplicate form of book illustrated in Fig. 1. In this construction, however, the front cover flap is longer than is shown in the construction shown in Fig. 1 and it is provided with a stub 43 which is mounted upon the pivot 34. The flap therefore is not adapted to swing but it does provide a pocket overlying the front cover into which used leaves may be swung. This flap may be ruled to provide a summary sheet as is shown in Fig. 7 and the corners may be cut away at 44 and 46 as hereinabove described in connection with the structure of Fig. 1.

This manifolding device includes a plurality of units wherein three copies are adapted to be made of each entry. Each unit includes the original and duplicate leaves 20 and 22, as described in connection with the construction of Fig. 1. The original record leaf 20 is connected to the duplicate leaf and folds thereover along a line of perforation 24. The duplicate leaf has a stub 32 and the leaf may be severed from the stub along the line of perforation 33. The stub is provided with an aperture 27 adapted to be received over the stud 34. The carbon leaf 28 is of the character shown in Fig. 3 and as used in Fig. 1 except that this carbon leaf is not here shown as adhesively secured to the stub of the duplicate leaf 22 but is independently pivoted upon the stud 34 as is the case in connection with the construction shown and heretofore described as Fig. 4. In this book, in order to provide three copies of each entry there is also included a heavy duty carbon sheet 47. This is bound in the book. It is not necessary that this sheet 47 be rotatable upon the stud as it is used through successive sets. It may be cut away

at one corner as at 48 to facilitate manipulation. After one set has been used and certain of the leaves have been detached and others have been moved into the pocket of the front cover the heavy duty carbon leaf 47 will be overlying the original record leaf 20 of the succeeding set. The upper right hand corner of the original record leaf is exposed through the cut out portion 49 of the heavy duty carbon leaf. The original record leaf may be grasped through this cut out portion 48 of the heavy duty carbon leaf and withdrawn from underneath such leaf and disposed thereover to put such succeeding set into condition for use.

The original record leaf 20 and duplicate record leaf 22 may be separated from the stub 32 of the duplicate record leaf and then divided for disposition. The used carbon leaf 28 may then be swung into the pocket. The stop sheet 40 is positioned underneath the next set and heavy duty carbon leaf 47 is inserted in the set underneath the original record leaf 20 overlying the carbon leaf 28 in the set. It will be seen that one entry is made upon the clean surfaced back of the carbon leaf 28 and that this carbon leaf itself serves the dual purpose of a transfer leaf and a record leaf.

In Fig. 9 I have illustrated a modified form of triplicate book wherein each unit includes five leaves. There is the original and duplicate record leaves 20 and 22 connected by a line of perforation 24 as hereinabove described. In addition there is a third clean surfaced record leaf 50 independently pivotally mounted upon stud 34. There is a one-time carbon leaf 28 likewise pivotally mounted upon the stud. There is a second one-time carbon leaf 29 likewise pivotally mounted upon the stud 34. Such a set provides three clean surfaced copies. The duplicate record leaf 22 may be detached from its stub along the line of perforation 33 such as shown in Fig. 8. The third clean surfaced record leaf 50 may be thrown back over the front cover flap 42 after it has been used and after the original and duplicate leaves 20 and 22 are removed and after the carbon leaf 28 has been swung back into the pocket and the carbon leaf 29 may then likewise be swung back into the pocket. It is of course understood that the duplicate record leaf 50 and even the carbon leaves 28 and 29 may be provided with lines of perforation separating them from their stubs if it were desired to have the same detachable from their stubs.

Fig. 6 is a cross section through the stud 34 as shown in Fig. 7, but in Fig. 6 this stud is shown as a tubular stud wherein the stud part 34 that is secured to the back 36 is adapted to receive a manifolding packet the leaves of which are held together by a tubular element 52 which slides over the stud 34. The front cover flap 42 is received over the stud 34 and the heavy duty carbon 47 is likewise received over the stud 34 and this stud is turned over as at 54.

Fig. 10 illustrates a modified form of triplicate book wherein each unit comprises merely three leaves. The book cover including the back 36, front cover 38, front cover flap 42, and pivot stud 34 may be as described in connection with the construction shown in Fig. 1. Each unit includes the duplicate record leaf 22 having a stub pivotally mounted upon the stud 34 and an original record leaf 20 and a one-time carbon leaf 28. A difference between this form and the form shown in Fig. 4 of the duplicate book is that in the form shown in Fig. 10 the back of the orig- 75

inal record leaf 20 is carbonized as in the "automatic" type of book while in Fig. 4 the original leaf is clean surfaced on both sides. The carbonized back of this original record leaf transfers 5 the record onto the clean surfaced side of the one-time carbon leaf 28 and this one-time carbon in turn transfers such record to the duplicate leaf 22. It will be seen that as the book is 10 operated the duplicate leaf 22 is provided with a line of severance along which it may be separated from its stub. One clean surfaced copy, leaf 22, is provided and the other copies, leaves 20 and 28, are black backed. The leaves 20 and 22 may be detached and leaf 28 swung into the pocket. 15 Fig. 11 illustrates a triplicate construction wherein there are four leaves, two of which are clean surfaced on both sides. It resembles the duplicate construction shown in Fig. 5 in that the cover structure is similar and each unit comprises the original record leaf 20, duplicate record leaf 22 and carbon leaf 28a adhesively secured at 44 to the back of the original record leaf. 20 In addition there is the one time carbon leaf 28 pivotally mounted on the stud 34. The original and duplicate record leaves may be detached 25 from the stub of the duplicate along the line of severance 33 and then in turn separated from each other along the line of severance 24 and carbon leaf 28a may be torn off the back of the original record leaf 20. The one time carbon leaf 28 may be swung into the pocket as has been heretofore described.

In Fig. 12 I have shown a modified form of back cover for the book. There is the usual back 30 36, front cover 38, front cover flap 42, and stop sheet 40. There is then provided a spring clip 35 of a generally U-shaped construction and illustrated in Figs. 12 and 13. One leg of this U is secured by rivets 56 to the back 36. The other 40 leg of the U is bent as illustrated and is of a resilient nature and is provided with lugs 58 for a purpose hereinafter described. The two legs of the U are provided with cooperating opposed pivot studs 60. A packet of manifolding leaves may 45 be secured together by a tubular rivet such as the rivet 34 shown in Fig. 6. In this connection such rivet might be turned over at both ends so as to hold the leaves in place. The packet of leaves with the tubular rivet will be inserted 50 within the clip and the studs 60 will engage in the opposite ends of the tubular rivet to hold the packet in place. Spring tension of the clip would be such as to hold the packets securely in position. The heavy duty carbon sheet would 55 have one end inserted underneath the lugs 58 and folded over the top of the uppermost leg of the spring clip so that the heavy duty carbon would be held by the lugs 58 against pivotal swinging movement. If desired, of course these 60 lugs might be omitted and the heavy duty carbon paper omitted and this spring clip used with the packet made up according to the duplicate style of book. The studs 60 might be made of such length that they would contact each other 65 at their opposite ends and perforated manifolding sets might be mounted therein without the employment of the tubular rivet but the tubular rivet would facilitate the insertion of the same.

Figs. 14 and 15 illustrate a modification wherein 70 the back cover 36 is provided with a pocket 62. The manifolding units may be assembled into a packet shown in Fig. 15 and held together by a rivet 64 turned over at its ends as shown. In Fig. 15 this packet is shown upside down and it is 75 provided with a back 66 which carries the stop

sheet 40 as a part thereof. A stub element 68 is likewise provided which is adapted to be received within the pocket 62 on the back cover to secure the packet in place for manipulation of the manifolding set. As shown in this form illustrated in Fig. 15 each set includes in addition to the original and duplicate record leaves 20 and 22 and the one time carbon leaf 28 a heavy duty carbon leaf 47 which is bound in the packet. A band 69 may have one end adhesively secured as at 70 to the back 66. The opposite end may be brought around over the front of the packet overlying the heavy duty carbon 46 and adhesively secured thereto and be itself mounted upon the pivot 64. This will hold the heavy duty carbon against 10 swinging but permit swingable movement of the one time carbon 28 in one direction at least about the pivot to a position overlying the front cover. The original and duplicate record leaves may be provided with lines of severance as hereinabove 15 described. The back of the front cover may be provided with end strips or pockets 71 adapted to receive opposite ends of a summary sheet 72 that may be inserted thereunder to keep a record 20 of the various entries made in the book. 25

Other changes according to well known manifolding practice might be made in the various forms here shown.

The term "book" where used herein describes an assemblage of a plurality of superimposed 30 manifolding sets or units whether mounted within a cover having a back and front cover or upon a carrier of any kind or assembled in superimposed relation for use. The term "back of the book" where used to describe the support for 35 the pivot stud describes any such support for a pivot stud upon which leaves are mounted for manipulation.

What I claim:

1. In a manifolding book, a back provided with 40 a leaf supporting pivot stud and a front cover provided with a flap substantially coextensive with said cover secured at one end to said stud, forming with the front cover a side opening pocket, a plurality of superimposed manifolding sets each 45 including a plurality of leaves, each set having at least one of its leaves pivotally mounted upon said stud for swingable movement thereabout to a position within the pocket formed between the front cover and its side flap. 50

2. A manifolding device having a leaf supporting pivot stud, a back and a front cover, a plurality of manifolding sets arranged in a single pile of superimposed sets, each set including a plurality of record leaves and a carbon leaf clean surfaced upon one face, each set having its carbon leaf pivotally mounted upon said pivot stud for swingable movement thereabout to a position overlying the front cover, and an additional carbon leaf positioned in the first set overlying the clean surface of the first mentioned carbon leaf and usable in the first set and in succeeding sets following use in the first set, said front cover having a flap secured to one edge overlying the cover and substantially coextensive therewith. 60 65

3. In a manifolding book, a back provided with a spring clip having opposed spaced apart cooperating pivot studs, a packet of superimposed sets of manifolding leaves secured together at 70 one end by a tubular connection, said packet having its connected end received within said clip with the pivot studs received within the opposite ends of the tubular connection whereby individual leaves of the packet may be pivotally 75

swung about said studs, and a heavy duty carbon leaf secured to said clip against pivotal movement but adapted to overlie successive sets of manifolding leaves in the packet.

- 5 4. In a manifolding book, a back provided with a U-shaped spring clip provided with cooperating opposed pivot studs carried by the opposed legs of the U-clip, a packet of superimposed sets of manifolding leaves gripped between the two legs 10 of the clip and pivotally secured upon the studs for swingable movement of individual leaves from a position within the packet to a position outside of the packet, and a heavy duty carbon leaf secured to the spring clip to overlie successive manifolding sets in the packet but held against pivotal swingable movement.
5. In a manifolding book including a back and a front cover attached thereto adapted to be folded over the back cover and enclose the contents therewithin, a pivot stud associated with the back adjacent to the point of attachment of the front cover thereto and adapted to receive and pivot thereon a plurality of manifolding leaves, said front cover having a side flap overlying the 25 front cover and of a size substantially coextensive therewith, said side flap hinged along one side edge thereof to the front cover and forming a side opening pocket into which leaves pivoted on said stud may be swung for retention therewithin.
- 30 6. In a manifolding book, a back provided with a leaf-supporting pivot stud and a front cover, a side flap of a size substantially coextensive with the front cover and secured thereto along one side edge of the latter to form in conjunction therewith a side opening pocket into which leaves

pivoted on said stud may be swung thereinto, a plurality of superimposed manifolding sets each including a plurality of record leaves and a carbon leaf, each set having at least one record leaf and one carbon leaf independently pivotally mounted upon said stud for swingable movement thereabout, the independent pivotal character of the carbon leaves enabling the same to be swung after use under the side flap where they are retained against contact with adjacent material.

5 7. In a manifolding book, a back provided with a U-shaped spring clip, the legs of which are provided with cooperating opposed pivot stud sections, and a packet of manifolding leaves inserted between the legs of the U-shaped clip and having an aperture therethrough through which the opposed pivot stud sections extend, certain of said leaves in said packet being pivotally swingable about the pivot stud sections through the open end of the U-shaped clip.

10 8. In a manifolding book, a back provided with a leaf supporting pivot stud, a plurality of superimposed manifolding sets each including at least one record leaf and at least one carbon leaf, each manifolding set having at least one record leaf 15 and a carbon leaf independently pivotally mounted upon said stud for swingable movement thereabout, the independent pivotal character of the carbon leaves enabling the same to be segregated after use from the record leaves by swinging the former about said pivot stud and by turning back the latter over the pivot stud without swinging movement thereabout.

ALBERT R. LAWSON. 35
